C. WILLIAMS, OF NEW YORK, N. Y.

Letters Patent No. 80,526, dated July 28, 1868.

IMPROVED APPARATUS FOR CLEANING SEWERS.

The Schedule referred to in these Letters Patent and making part of the same.

TO ALL WHOM IT MAY CONCERN:

Be it known that I, C. WILLIAMS, of the city, county, and State of New York, have invented certain new and useful Improvements in Apparatus for Cleaning Sewers; and I do hereby declare that the following is a full, clear, and exact description of the same, reference being had to the accompanying drawings, making a portion of this specification, in which—

Figure 1 is a vertical longitudinal section, showing my invention, and the manner of employing the same in cleaning a sewer.

Figure 2 is a detached side view of one portion of my invention.

Figure 3 is a transverse section of the same.

Figure 4 is a longitudinal section of the same.

Figure 5 is a longitudinal section, showing one portion of the invention as employed in cleaning a small or pipe-sewer.

Figure 6 is a plan view of another portion of the invention.

Similar letters of reference indicate corresponding parts in all the figures.

The object of this invention is to enable sewers to be cleansed from the solid and semi-solid sediment and deposits collected therein with greater convenience and facility, and consequently at a much less cost than has hitherto been practicable, and to this end the invention consists in certain novel means, appliances, and combinations of parts whereby the object mentioned is effectually secured.

The sewer is shown at A, and is furnished at intervals with man-holes or openings, A*; and in suitable proximity with two adjoining man-holes A* are derricks or cranes, B, of any suitable construction, and furnished with pulleys and lifting-apparatus, in such manner that a draught-rope, B*, passed through the section of the sewer between the two man-holes, and having its ends connected with the cranes, may be worked or drawn to and fro within the said section, the draught-rope being passed through the said section in the first instance by means of a jointed rod, elongated when in use by the addition of successive lengths.

The draught-rope, just mentioned, is provided with two buckets, C C*, placed at a suitable distance apart, with that portion of the rope between them provided with loops or links, a, and at one or both ends with a hook, b, in such manner that the length of rope between the buckets may be lengthened or shortened as circumstances may require, and as hereinafter fully set forth.

Inasmuch as the buckets are designed to be employed not only as lifting-vessels but also as scrapers, and as the several features embodied therein are intended to be employed under widely-varying circumstances, the said features may be described in detail, as follows:

That which constitutes the bottom of the bucket, when the same is used for lifting purposes, consists of two flat leaves, c, hinged at their inner edges to each other and to a suitable support, which, in the case just mentioned, may be a transverse rod, C', fixed in the bottom of the body d of the bucket, as shown in figs. 1 and 4, so that when the bucket is drawn forward in the sewer, as hereinafter further set forth, the leaves will spread out to close the bottom of the aforesaid body, and enable the same to hold the material contained therein, and so that when the bucket is drawn backward the said leaves will be brought flat against each other to open the said bottom, and enable the bucket to be drawn back through the deposits in the sewer, with very slight resistance therefrom, the two leaves constituting, in fact, a valve-bottom for the bucket. In those cases where it is desired to employ this feature of the invention in clearing out so-called pipe-sewers, or those of small diameter, the leaves may be placed upon a rod situated at right angles to their hinge, as shown in fig. 5, and instead of one pair, two or more sets may be employed, the operation of the leaves in this case being substantially the same as in that first mentioned, except that the deposit is simply scraped or drawn through or from the sewer by the forward movement of the leaves, instead of being confined within the body of the bucket.

In order to obviate the necessity of removing from the sewer the large proportion of water mingled with the sediment or deposit in the sewer, the body d is perforated with numerous holes, as shown in figs. 1, 2, 3,

and 4, the said holes being of such size as to permit the water to flow out through them without allowing the escape of the more solid contents of the bucket.

The bail or handle, by which the draught-rope is attached to the top or open end of the bucket, is shown at *e*, and is pivoted at or near the centre thereof, and is provided with a slot through which passes the curved brace *f*, fixed upon the aforesaid end of the body of the bucket in such manner that by means of a set-screw the bail may be fixed thereto at any angle to the longitudinal axis of the bucket, to the end that the said bail may be secured so that its forward end will be higher than its rear extremity when the bucket is drawn through the sewer, so that the open end of the said bucket will be inclined downward, as shown in fig. 1, to insure the ready passage into it of the sediment or deposit to be removed.

In order to still further facilitate this filling of the bucket, the body *d* thereof is made oval in its cross-section, as shown more fully in fig. 3, one of the flattened sides of the said body being downward when the bucket is drawn through the section of the sewer, as hereinbefore indicated.

Situated at one side of each man-hole, and within the sewer, as shown in fig. 1, is a pulley, *g*, designed to guide the draught-rope in operating the buckets, and which is attached to a holding-device, *D*, constructed as follows:

The horizontal and parallel bars *h*, to one end of which the pulley *g* is pivoted, have pivoted between them, at the ends opposite the pulley, two bars, *i*, to the extremities of which are pivoted two crossed bars, *j*, which are connected at their centres by a transverse pin, *a'*, the ends of which work in slots, *aX*, formed lengthwise in the bars *h*, the several bars being so arranged that the strain of the draught-rope upon the pulleys *g*, by tending to bring the bars *i*, *j* into a position more nearly parallel with each other, forces the ends of the same against the adjacent sides or surfaces of the sewer with a pressure proportioned to the strain exerted upon the pulley *g*, a means whereby the said pulley may be quickly and conveniently secured in place, being in this manner secured.

In order that the draught-rope may be readily placed upon or thrown off from the pulley *g*, the pivot of the latter is attached to the device *D* only at one end, as shown more fully in fig. 6, and to assist in guiding the draught-rope in placing the same over the pulley, as hereinafter more fully explained, a curved arm or guide, *m*, is attached to the aforesaid device in such manner that a passage or way is formed, as shown at *m***, through which the rope may be passed behind the pulley by means of a hook or other suitable appliance.

Placed at the inner side of each man-hole is a friction-roller, *mX*, upon which the draught-rope runs when not upon the pulleys *g*, just mentioned.

Placed over each of the two man-holes is a horizontal frame, *E*, in the centre of which is a vertical hole, *e'*, through which the draught-rope passes, the said frames serving to so guide the rope that the buckets, in their vertical movement, may pass properly up through the man-holes.

In the operation of the apparatus, that pulley *g*, at the man-hole through which it is desired to draw the bucket, has placed over it the contiguous portion of the draught-rope, and the buckets are arranged by the means hereinbefore described, at such distance apart that when one bucket is elevated above the man-hole through which it passes, the other, adjacent to the pulley upon which the rope is passed, will be brought within the sewer to such distance from the other man-hole as may be necessary to enable it to be filled when drawn forward, which being done, the elevating-apparatus is operated to draw the bucket last mentioned forward, until it is brought underneath the man-hole toward which it moves, whereupon the draught-rope is thrown, by any suitable means, from the pulley *g* at the said man-hole, whereupon the continued movement of the draught-rope draws the bucket up through the man-hole to the desired height, the frame being lifted by the bucket as it rises. The other bucket, in the meanwhile, is brought back into the sewer through the other man-hole, and at such distance therefrom that the movement of the draught-rope being reversed, the said bucket will be filled, and afterward raised in the same manner as the one first described; the sediment being thus removed by the alternate action of the two buckets, the removal commencing at the ends of the section between the man-holes, and progressing inward to the centre thereof until completed, the length of that portion of the draught-rope between the buckets being adjusted, as hereinbefore described, as may be required, to bring the buckets the required distance within the sewer at the different stages of the operation of removing the sediment therefrom, as set forth.

The bucket on entering the sewer goes with its bottom downwards, and when it strikes the sediment the leaves *c*, *c* open inwardly and allow the body of the bucket to cut through the sediment as it is being drawn, by the rope attached to its bottom, into the sewer, until it has filled with the sediment; the motion is then reversed, whereupon the sediment within the bucket causes the said leaves to spread, closing the bottom, and thereby retaining its contents, to be drawn out of the sewer in the manner hereinbefore described. Each time this operation is performed the buckets may be linked closer together than at the preceding time, thus causing them to travel farther into the section, between the two man-holes, until they each travel to a little beyond the centre.

What I claim as my invention, and desire to secure by Letters Patent, is—

1. The toggle-arms *i*, *i*, braces *j*, *j*, and head *D*, carrying the sheave *g*, combined and operating to hold the pulley, substantially as and for the purpose described.
2. The guide-piece *m* on the dog *D*, to facilitate the introduction of the rope to the sheave *g*, substantially as set forth.
3. The folding scraper *c*, fig. 5, constructed and arranged for clearing pipe-sewers, substantially as shown and described.

4. The automatically-folding leaves *c c*, arranged in the bucket *C*, constructed as shown, and for the purpose set forth.
5. The adjustable bail *e*, in combination with the fixed bail *f* of the bucket *C*, substantially as and for the purpose specified.
6. The bucket *C*, made with perforated sides, as and for the purposes set forth.
7. The detachable guide-frames *E*, arranged upon the man-holes of a sewer, in combination with the draught-rope *B**, substantially as and for the purposes described.

C. WILLIAMS.
